UNITED STATES PATENT OFFICE

HOWARD T. WALTON, OF COLLINGSWOOD, NEW JERSEY, ASSIGNOR TO DAVID LUPTON'S SONS COMPANY, OF PHILADELPHIA, PENNSYLVANIA, A CORPORATION OF PENNSYLVANIA

VENTILATING SYSTEM

Application filed October 22, 1928. Serial No. 313,974.

This invention relates to ventilating systems intended for use more particularly in buildings of industrial plants in which explosives are manufactured or used, or in which explosive materials are developed or highly combustible gases generated, incidental to manufacturing processes.

More specifically speaking, the present improvements are concerned with a ventilating system wherein extensible members are incorporated with the mechanism provided for normally operating the ventilating closures, such that, in the event of an explosion, the closures are permitted to open automatically for relief of attendant internal pressure to the end of precluding destruction of the buildings and minimizing casualties among workers employed therein. A typical protective ventilating system of this character is disclosed in U. S. Letters Patent application, Serial No. 314,000 concurrently filed herewith by Joseph H. Sheard, and attention is therefore directed to the said application for the purpose of reference.

In connection with a ventilating organization of the kind referred to, I aim to provide means whereby the system may be set to function automatically under different explosive pressures, and thus adapted to the various conditions or requirements likely to be met with in practice.

A further object of my invention is to enable—through provision of simple and inexpensive adjuncts—restoration of the system for normal operation after an explosion by manipulation of the mechanism employed for actuating said closures ordinarily.

How the foregoing as well as other objects and attendant advantages can be readily realized in practice will be manifest from the detailed description which follows in connection with the attached drawings, wherein Fig. I is a vertical sectional elevation of a building ventilating system conveniently embodying my invention.

Fig. II is a fragmentary plan view of the system.

Fig. III is a longitudinal detail sectional view, on a larger scale, of a novel extensible member constituting a feature of my inven-

tion, its component parts being shown in the positions which they normally occupy; and,

Fig. IV is a view, similar to Fig. III, showing how the parts of the extensible member are distended in permitting automatic opening of the ventilating closures responsively to the pressure of an explosion within the building.

The ventilating system chosen for the purposes of illustration herein is of the kind comprising continuous longitudinal closure sashes 10, which are arranged in vertically-spaced relation and pivoted along their upper edges as at 11, so as to be swingable to the open position, shown by dot-and-dash lines in Fig. I. The supporting structure for the sashes 10 may include longitudinals or horizontals 12 to take the hinges 11 and to function as stops for the lower or swinging edges of the sashes 10, as well as uprights 13 to sustain said horizontals. To enable operation of the vertically-arranged sashes 10 in unison, links 15 are employed to connect arm prolongations 16 of the side rails of said sashes, the prolongations 16 extending inwards and upwards of the pivots 11.

The means which I provide for operating the sashes 10 embodies a screw 17 having end projection beyond opposite sides of a laterally-slotted bearer housing 18. This housing is bolted or otherwise secured to a shelf in the form of a short horizontally arranged channel piece 19 suitably attached to the uprights 13 (Fig. II) of the sash supporting structure. Affixed to the screw 17 within the bearing housing 18 is a sheave 21 capable of actuation either manually, or by power, through a chain 22. As shown in Fig. II, the ends of the screw 17 are oppositely threaded as at 17^a, 17^b, and respectively engage pivoted follower blocks 23, on motion multiplying levers 24, which are counterparts of one another and fulcrumed at 25, on the channel piece 19. The outer ends of the levers 24, lie in different planes for capacity to overlap, as illustrated in Fig. II, and terminate in cross arms 24^a, formed as integral transverse prolongations of the levers 24, or made separate and rigidly attached to said levers by riveting or welding as found most expedient in practice. The

movement of the levers 24, is communicated to the closure sashes 10 by means of connecting members 26, which, as later on explained, are exactly alike in construction and arrangement. For convenience in the present instance, the members 26, are coordinated with the lower sash 10 of the group shown in Fig. I; and the links 15, previously referred to, are relied upon to impart corresponding movement to the upper sash 10. From Figs. I and II it will be noted that the members 26, are pivotally connected at one end to the bottom rail of the lower sash 10 at remotely spaced points 27, and, at the other end, are similarly connected to the outer extremities 5 of the cross arms 24^a, of the levers 24, at 28. With this arrangement, rotation of the differential screw 17 in one direction through actuation of the sheave 21 by the chain 22, 10 will result in relative outward movement or separation of the levers 24 from the position illustrated and opening of the sashes 10, with concurrent sliding movement of the screw 17 in the slotted bearer housing 18; while rotation of the screw 17 afterwards in the opposite direction will be attended by relative approach of the levers 24 and a reverse sliding of the screw 17 with closing of the sashes 10. Through a pair of longitudinally extending rods 29, 30 having pivotal connection 15 with the cross arms 24^a, of the levers 24, at 31, 32 respectively, and by duplication of all the operating parts hereinbefore described except for the screw 17, its housing 35 18, and sheave 21 (which are intended to serve as a "master" means) corresponding opening and closing movement may be imparted to said sashes at distributed points 20 along their length.

Referring now to Figs. III and IV, it will be noted that each of the members 26 is rendered extensible as a consequence of construction with two relatively slidible sections 26^a, 26^b. The section 26^a is made tubular and 25 suitably formed at one end with a clevis 35 for pivotal connection at 27 to the closure sash 10, and at the other end fitted with a short diametrically-enlarged extension 36. The section 26^b, on the other hand, is made 30 from rod stock, and is telescopically received within the section 26^a which, as shown, is provided with a bearing-bushing 37 to assist in maintaining the rod centralized. One end of the section 26^b is flattened and pierced 35 as at 38 for pivotal connection at 28 to the cross arms 24^a of the corresponding lever 24, and the other end equipped with a head 39 having a slide fit within the tubular section 26^a. Near its outer end, the rod section 40 40 moreover carries a collar 40, which normally occupies the hollow of the enlarged extension 36 of the section 26^a, as shown in Fig. III. This collar 40 has a rounded circumferential cam depression 40^a adapted to be 45 engaged by the correspondingly rounded

projection 41^a of a latch member 41 pivoted to a lug 42 exteriorly of the extension 36 of the section 26^a, the projection 41^a aforesaid reaching inwards through a slot 43 in the extension 36. The latch 41 is urged toward 70 the collar 40 by a helical spring 45 enclosed in a lateral hollow boss-like offset 46 of the extension 36; and an adjustable abutment screw 47 is provided to enable regulation of the spring pressure for a purpose presently 75 set forth. The latch 41 thus functions as a coupling instrumentality to prevent relative sliding of the sections 26^a, 26^b of the extensible link members 26 incidental to normal 80 operation of the ventilating system. In the event, however, of an explosion within the building and induction of lengthwise strain on the members 26, as the force of the explosion exerts itself upon the sashes 10, the latches 41 will obviously yield to dislodgment 85 from the depressions 40^a in the collars 40 thereby permitting extensible action of the sections 26^a, 26^b after the manner illustrated in Fig. IV, and automatic opening of the sashes 10. In this connection, it is to be observed that, by virtue of the facilities for regulating the latch springs 45, the system may be set to function automatically under different explosive pressures, and thus be adapted 90 to any special requirement or conditions 95 of practice.

When once opened under the force of an explosion, the sashes 10 are so held for continued relief of attendant pressure within the building, by action of counterweights 50 pivotally suspended, as shown in Fig. II, from the arm prolongations 16 of the lowermost sash 10.

The extent of sash opening under manual operation, or under automatic operation in 105 the event of an explosion as just explained, is limited by stop means shown in Figs. I and II as embodying a rod 51 with pivotal attachment at 52 centrally of the bottom rail of the lower sash 10. This rod 51 passes 110 through a slotted stop bracket 53 secured medially of the channel piece 19, and at the free end carries a collar 54 to co-operate with the stop bracket 53 in limiting the opening 115 of the sash 10 as aforesaid. The stop means 51 also serves as an aid in enabling restoration of the extensible members 26, to the normal condition through operation of the sash actuating mechanism in the usual way. In other words, it will act to resist the thrust 120 of the extensible link members 26, as the rod sections 26^b are moved forward to bring their collars 40 once more into the province of the latches 41 and thereby effect automatic re-coupling with the tubular sections 26^a. To 125 facilitate such re-coupling, the leading ends of the collars 40 are beveled as at 40^b as shown in Figs. III and IV, so as to readily re-enter the enlargements 36 of the sections 26^a at the inception of the movement, and then to de- 130

press the latches 41 in opposition to their springs 45 until the circumferential depressions 40^a of the collars 40 are brought into registry with the projections 41^a, of said latches 41, when engagement will automatically take place, in a manner obvious from Figs. III and IV, whereupon the system may again be manually operated in the manner already fully understood.

Having thus described my invention, I claim:

1. In a building ventilating system of the character described, a closure with mechanism for normally operating it, mechanism embodying means permitting the closure to open automatically under pressure of an explosion within the building, and counter-weight means influential upon the closure in holding it in open position after the explosion.
2. In a ventilating system of the character described with a closure hinged along its upper edge and mechanism for normally operating the closure, means permitting the closure to open automatically under pressure of an explosion within the building, and counter-weight means influential upon the closure in holding it in open position after the explosion.
3. In a building ventilating system of the character described, a closure and mechanism for normally operating it embodying extensile members with sections capable of sliding relatively to permit opening of the closure automatically under pressure of an explosion within the building, and counter-weight means influential upon the closure in holding it in open position after the explosion.
4. In a building system of the character described, a closure and mechanism for normally operating it, said mechanism embodying extensile members with sections capable of sliding relatively to permit opening of the closure automatically under pressure of an explosion within the building, and means for coupling the sliding sections of the extensile members with provision for adjustment to yield under different explosive pressures.
5. In a building ventilating system of the character described, a closure and mechanism for normally operating it, said mechanism embodying extensile members with sections capable of sliding relatively to permit opening of the closure automatically under pressure of an explosion within the building, and means for coupling the sliding sections of the extensile members with a capacity for adjustment to yield under different explosive pressures including a latch on one of said sliding sections to engage a rounded cam notch in the other, a spring pressing on the latch, and a screw to regulate the pressure of the spring.
6. In a building ventilating system of the character described, a closure and mechanism

for normally operating it, said mechanism embodying extensile members with sliding sections coupled by latch means capable of yielding to permit the closure to open under pressure of an explosion within the building, counter weight means influential upon the closure in holding it in open position after the explosion, and stop means for limiting the extent of opening and preventing movement of the closure incidental to subsequent re-coupling of the extensile member sections by actuation of the operating mechanism aforesaid.

7. In a building ventilating system of the character described, a closure and operating means therefor including a motion-multiplying lever and a screw for moving said lever, an extensile member connecting the lever with the closure, said member comprising sections capable of sliding relatively to permit opening of the closure automatically under pressure of an explosion within the building, and counterweight means influential upon the closure in holding it open after the explosion.

In testimony whereof, I have hereunto signed my name at Philadelphia, Pennsylvania, this 13th day of October, 1928.

HOWARD T. WALTON.
